(57) **CLAIM**

The ornamental design for a snow stake driver, as shown and described.

DESCRIPTION

FIG. 1 is a perspective view of a snow stake driver, showing my new design.

FIG. 2 is a left side view of the snow stake driver of FIG. 1. The right side view is a mirror image of the left side view.

FIG. 3 is a front view of the snow stake driver of FIG. 1.

FIG. 4 is a rear view of the snow stake driver of FIG. 1.

FIG. 5 is a top view of the snow stake driver of FIG. 1; and, FIG. 6 is a bottom view of the snow stake driver of FIG. 1.

Any broken line portions of FIGS. 1-6 are included to show unclaimed subject matter only and form no part of the claimed design.

1 Claim, 3 Drawing Sheets(56)
